UNITED STATES PATENT OFFICE

PERCY E. GOODWIN, OF EVANSVILLE, INDIANA, ASSIGNOR TO THE STEEL SCAFFOLDING COMPANY, OF EVANSVILLE, INDIANA, A CORPORATION OF INDIANA

SCAFFOLD BRACKET

Original application filed June 4, 1927, Serial No. 196,547. Divided and this application filed October 25, 1927. Serial No. 228,665.

This invention relates to scaffold brackets of the general class adapted for use on the walls of wooden buildings and other structures to serve as a supporting means for 5 planks or platforms on which workmen may stand.

One of the objects of the invention is, to provide a foldable scaffold bracket having an improved attaching bolt or connector which 10 will require boring or cutting of only a small hole through the sheathing in order to connect the bracket to the wall of the building, instead of necessitating the cutting of a relatively large hole such as is necessary with those 15 brackets having a hook to engage the studding. In practice the hole which has to be cut will only be five-eighths of an inch in diameter and, being small, it can be readily patched when the coat of stuccoing is applied, 20 whereas with those brackets employing a hook to engage the studding, it has been necessary to cut a hole some two by three inches in size which is difficult to patch.

In connection with the present invention, it 25 is only necessary to provide a block through which the improved bolts connection passes, such block serving as a bearing piece for the handled nut employed on the bolt.

Another object of the invention is to provide 30 a foldable scaffold bracket provided with means whereby an improved toeboard and hand rail attachment may, if desired, be attached thereto in such manner that it may be locked in upright position so that a toeboard 35 and hand rail may be connected thereto, or, be folded down on the bracket in compact arrangement for handling or transportation.

The present application is a division of 40 Serial No. 196,547, filed June 4, 1927.

A practical embodiment of the invention is 45 shown in the accompanying drawings, in which:

Figure 1, is a perspective view of the scaffold bracket when extended, ready for use;

Fig. 2, is a similar view showing the scaffold bracket in use on the wall of a wooden building, illustrating how the improved toeboard and hand rail attachment of my Patent No. 1,650,939 may be used in connection therewith, if desired.

Fig. 3, is a perspective view of the scaffold bracket alone, when in folded arrangement;

Fig. 4, is a detail perspective view showing the manner in which the scaffold bracket is connected to the building when in use;

Fig. 5, is a detail view showing the pivot and lock; and

Fig. 6, is a section on the line 6—6 of Fig. 5.

Referring first to Fig. 1, the scaffold bracket comprises a bar or support 1 provided with an upwardly projecting retainer 2 to prevent the plank or other platform supported by said bar from accidentally slipping off of it when the bracket is used alone. The bar is provided with holes 3, 4, whose purpose will 65 presently appear.

The main supporting braces or legs are shown at 5 and 6, being pivoted by means of a bolt 7 or rivet to the outer part of the bar 1. These braces have bent feet 8 which 70 may have openings to receive nails driven into the wall of the building on which the bracket is used, or these openings may be omitted. The braces 5, 6, are preferably of angle iron for the sake of strength and they 75 are connected by a cross piece 9 which is preferably riveted thereto and which may be of angle iron. The supporting braces being spread apart to a considerable extent and rigidly connected by the cross piece 9, they 80 afford a wide bearing on the side of the building and prevent lateral movement of the bracket.

A tie or hanger 10 straddles the bar 1 and is pivoted to the braces 5, 6, as shown at 11. 85 As shown, this tie or hanger 10 is made of a single piece of bent rod whose apex 12 is sufficiently broad to permit it to slide on the bar 1 when adjusting the bracket or when folding or extending it.

I wish it to be understood, however, that the tie or hanger 10 does not have to be made of a single piece nor is it necessary to pivot the hanger to the braces 5, 6 in the specific manner shown at 11 where the ends of the 90 tie or hanger are bent outwardly and are received in holes in the braces 5, 6.

It is also to be understood that the part of the tie or hanger which straddles the bar 1 100 may be of any suitable construction and not,

necessarily, the bent part or apex illustrated, as it is well within the spirit of the construction in question to provide a special hanger at the upper part of the tie 10 where it is supported by the bar 1.

The tie or hanger 10 transmits directly to the supporting braces 5, 6 any weight imposed upon either side of the supporting part 1, thus preventing any twisting motion which would result in the "walking" of the feet 8 on the wall of the building.

15 My present improvements reside in the improved means for attaching the bar 1 to the building and in the provision of the holes 3 and 4, other features of the construction shown in Fig. 1 being substantially disclosed in the patent to Bonenberger and Goodwin No. 1,125,051.

The improved attaching means for the scaffold bracket comprises a bolt or member 13 which, as shown, is a flattened part 14 riveted or otherwise secured or fastened to the inner end of the bar 1 as shown at 15. Instead of using a separate member 13, the bar 1 may be provided with an integral member 13.

The member 13 is provided with screw threads 16 for a considerable portion of its length and it carries a handled nut 17 engaged with said screw threaded part.

The manner in which this connection is used is shown in Figs. 2 and 4. A hole, say five-eighths of an inch in diameter, if that be the size of the member 13, is bored through 35 the studding 18 to which the sheathing 19 of the wall of the building is attached. It is then only necessary to pass the member 13 through this hole and to provide a separate block 20 with a corresponding hole 21 in 40 order to anchor the bracket in the position shown in Fig. 2, when the handled nut has been applied and tightened up against the block 20. The block 20 serves as a bearing block for the handled nut 17 and distributes 45 the strain over a sufficient area of the studding 18 to securely hold the bracket.

50 A very considerable advantage is obtained by the use of this improved connection because it is only necessary to bore a small hole to enable the bracket to be attached to the building, whereas with those brackets which employ a hook or special connection adapted to engage around the studding, it is necessary to cut a hole having an area of several square inches, usually, a hole of at least two by three inches in size.

As thus far described, the bracket which is shown alone in Figs. 1 and 3, is intended for use by itself without the combined hand rail and toeboard attachment which is shown as connected thereto in Fig. 2.

The provision of the holes 3, 4, however, adapts the scaffold bracket to be used in combination with the hand rail and toeboard attachment as shown in Fig. 2 so that the

complete bracket fulfills the requirements of the laws of those States which make it necessary to provide means to prevent the workmen or artisans from stepping off of the scaffold or from falling therefrom.

The combination toeboard and hand rail holding attachment or bracket comprises a bar 22, preferably of angle iron, which carries at its lower end a plate 23, riveted connections 24 preferably being provided to prevent accidental dis-connection. The plate 23 has a bolt hole through which passes a removable hinge bolt 26. When the bar 22 is unlocked, it is not necessary to detach the hinge bolt 26 which then acts as a pivot, enabling the complete scaffold to be folded into compact form, inasmuch as the bolt 26 passes through hole 3. 75 80

For the purpose of locking the bar 22 in upright position, there is provided an improved J-shaped locking bolt 27 which has its screw threaded shank passing through a hole 28 in the plate 23 and carrying a handled nut 29. Between the nut and the plate 23 are washers 30. The hook part of the bolt is adapted to enter the hole 4 in the part 1 when the nut 29 is tightened, thus locking the bar 22 in the upright position shown in Figs. 2, 5, 6. As the J-shaped or hook-shaped bolt is carried by the plate 23, it is only necessary to loosen the handled nut 29 sufficiently to enable the hook of the bolt to be withdrawn from the hole 4, in order to unlock the bar 22, as the pivot bolt 26 need not be taken off. When thus unlocked, the entire combination bracket may be folded, the parts being in compact relation, so that the bracket occupies only a minimum amount of space and can be readily carried about or stacked with other brackets for transportation.

The hook shaped clamp bolts 34 and 35 having screw threaded shanks and provided with handled nuts 39, 41, are carried by the bar 22 and adapted to hold the hand rail 38 and the toeboard 37.

The scaffold or platform which is supported by the bars 1 of the different brackets shown in Fig. 1 which are connected to the side of the house or building, appears at 43 and, according to usual practice, may comprise planks or boards laid edge to edge. 115

It will be observed that while the scaffold bracket is shown in Fig. 2 as combined with means adapted for use in connection with the toeboard and hand rail attachment, in order to comply with the law in those localities where this protection is required, nevertheless, the scaffold bracket is intended to be used by itself, as shown in Fig. 1 and is then secured to the wall of the building as illustrated in Figs. 2 and 4, or, may be folded into compact form as shown in Fig. 3. 120 125

What I claim is:

1. The combination with a scaffold bracket comprising a horizontal supporting bar having

ing means at one end to effect locking engagement with the wall of a building, and at its other end being provided with a pair of holes, of an upright bar having two fasteners, respectively detachably received in the said holes and locking the upright bar to the horizontal bar at the outer end of the latter, legs attached to the outer part of the horizontal bar inwardly of the two holes aforesaid, and 5 extending in downwardly inclined diverging relationship below the horizontal bar and having their free ends adapted to bear against the wall of a building, and a hanger suspending the legs from the horizontal bar and freely 10 slideable therealong when the scaffold bracket is being folded.

2. A scaffold bracket of the class embodying a horizontal bar, legs attached to the outer part of the horizontal bar and extending 15 downwardly in inclined diverging relationship below the horizontal bar and having their free ends adapted to bear against the wall of a building, and a hanger suspending the legs from the horizontal bar and freely 20 slideable therealong when the scaffold bracket is being folded, characterized by a screw threaded anchoring extension constituting a continuation of the horizontal supporting bar at its inner end and adapted to be passed 25 through an opening in the wall of a building, and a tightening or retaining screw-threaded-nut carried by said screw threaded extension and adapted to engage the inside of the wall to which the bracket is applied, the aforesaid 30 hanger being entirely independent of, and 35 having no connection with, the aforesaid screw threaded anchoring extension.

In testimony whereof I affix my signature.
PERCY E. GOODWIN.
